UNITED STATES PATENT OFFICE

MADGE S. MOSELEY, OF MEMPHIS, TENNESSEE

BOOK HOLDING ATTACHMENT FOR TYPEWRITERS

Application filed October 9, 1930. Serial No. 487,567.

This invention relates to an attachment for a typewriter and pertains particularly to an attachment designed to support a typist's notebook.

6 The primary object of the present invention is to provide a notebook support which may be easily and quickly applied to the frame of a typewriter and after attachment thereto may be allowed to remain without interfering with the operation of the machine.

Another object of the invention is to provide an easily and quickly detachable device of the above described character, which will support the operator's notebook at the proper 15 level and angle to enable her to take notes therefrom while typing with ease and comfort.

A still further object of the invention is to provide a book supporting device of the above 20 described character which is designed to be economically produced and may therefore be retailed at a relatively low price.

The invention will be best understood from a consideration of the following detailed description taken in connection with the accompanying drawings forming part of this specification, with the understanding, however, that the invention is not confined to any strict conformity with the showing of the drawings 25 30 but may be changed or modified so long as such changes or modifications mark no material departure from the salient features of the invention as expressed in the appended claims.

35 In the drawings:

Figure 1 is a view in top plan of a portion of a typewriter showing the device embodying the present invention applied thereto.

Figure 2 is a view in side elevation of the 40 device.

Figure 3 is a rear view of the same.

While the present invention is of a character that will permit of its being attached to any make of typewriter with only slight alterations thereto to fit the particular machine, it has been shown in the accompanying drawings as being attached to a typewriter of the make known as a Remington. In view of the fact that only a slight change in the contour 45 50 of one of the supporting arms for the device

must be made in order to adapt the device to typewriters of other makes, it is to be understood that the device is not to be limited to use upon the particular type of machine shown.

Referring more particularly to the drawings, the numeral 1 indicates generally a portion of the left hand side of a typewriter of the make above named. In this particular type of typewriter the mechanism is enclosed by a casing 2 in the top of which a channel 3 is formed which has an opening 4 formed in the forward wall thereof a slight distance inwardly from the left end. At the front of the machine the keyboard is surrounded by a frame 5, the left side bar of which is indicated by the numeral 6.

The device embodying the present invention comprises an elongated rectangular plate 7 which, at one end, has formed thereacross a flange 8 which serves to support a notebook in position while in use.

Secured transversely of the back of the plate 7 is a pair of spaced sleeves, the upper one of which is indicated by the numeral 9 while the lower one is indicated by the numeral 10.

The upper sleeve 9 receives in one end the right angularly extending terminal portion 11 of a relatively long supporting bar 12 which, when the device is in applied position on the typewriter, extends transversely of the left side thereof and adjacent the top, as illustrated. The rear end of the arm 12 has a right angularly extending portion 13 which is directed oppositely from the portion 11 and extends longitudinally of the channel 3 of the machine casing to the aperture 4 in the front wall thereof, where it terminates in a forwardly extending hook 14 which engages in the aperture 4 in the manner shown.

The lower sleeve 10 upon the plate 7 carries a bar 15 which, like the portion 11 of the arm 12, is of circular cross-section, and the outer end of this bar 15 is formed to provide a hook 16 which engages over the adjacent side bar 6 of the frame surrounding the typewriter keyboard. As the bar 15 and the portion 11 of the arm 12 are round, it will be seen that they may be oscillated in the sleeves.

9 and 10 in which they are placed so that tilting of the plate 7 within certain limits is permitted thus enabling the user to arrange the plate at the proper inclination.

5 From the foregoing description it will be readily seen that the present device forms a desirable addition to a typewriter by means of which an operator thereof may support her notebook in such a manner that the transcribing of notes therefrom may be accomplished without difficulty.

Having thus described my invention, what I claim is:

1. An attachment for typewriters having 15 a mechanism enclosing structure and a key enclosing frame at the front thereof, comprising a plate, means at one edge of said plate for engaging the edge of a book placed thereagainst, an arm oscillatably attached to and 20 projecting laterally from one side of said plate adjacent one end and adapted to engage said key enclosing frame, and a second arm oscillatably attached to the plate and projecting laterally from the said side 25 and formed for engagement with the mechanism enclosing structure.

2. A book-holding attachment for typewriters having a mechanism enclosing structure and a key enclosing frame disposed at the 30 front thereof, comprising a plate, a book-engaging flange formed along one edge of said plate, a bar mounted transversely of the plate and having a hook at one end adapted to engage said key enclosing frame, an arm having one end turned at right angles and disposed beneath said plate, means for securing 35 said end of said arm to the plate, and a lateral extension formed at the other end of said arm and directed oppositely to the right angularly extending portion thereof and adapted to 40 be attached to an adjacent portion of the mechanism encasing structure said plate being oscillatable on the arm and bar for adjustment for inclination.

3. A book-holding attachment for typewriters having a mechanism-enclosing structure and a key-enclosing frame disposed at the front thereof, comprising a plate, a book-engaging flange formed along one edge of 50 said plate, a bar mounted transversely of the plate and having a hook at one end adapted to engage said key enclosing frame, an arm having one end turned at right angles and disposed beneath said plate, means for securing 55 said end of said arm to the plate, and a lateral extension formed at the other end of said arm and directed oppositely to the right angularly extending portion thereof and adapted to be attached to an adjacent portion 60 of the mechanism-encasing structure, said right angularly extended portion of the arm and said bar being oscillatable on the plate to facilitate the angular adjustment of the plate relative to the vertical.

4. A book-holding attachment for type-

writers having a mechanism-enclosing casing and a key-enclosing frame disposed at the front of the casing, comprising a plate having a flange along one edge, a pair of bearing sleeves extending in spaced parallel relation 70 transversely of the face of the plate opposite that from which the flange projects, a bar extending through one of said sleeves projecting beyond one side edge of the plate and terminating in a hook adapted to engage said 75 key frame, said bar being oscillatable in the sleeve, and an arm having two portions arranged in spaced parallel relation and an intermediate portion connecting the spaced 80 portions and disposed at right angles thereto, said spaced portions being oppositely directed from the ends of the intermediate portion, one of said spaced portions being oscillatably held in the other of said sleeves with the intermediate portion positioned beyond the side 85 of the plate adjacent the hook of said bar, and the other portion terminating in a hooked end designed to engage in an aperture in said casing.

In testimony whereof I hereunto affix my 90 signature.

MADGE S. MOSELEY.
